UNITED STATES PATENT OFFICE.

CHARLES H. PELTON, OF SPRINGFIELD, OHIO, ASSIGNOR TO THE THOMAS MANUFACTURING COMPANY, OF SPRINGFIELD, OHIO, A CORPORATION OF OHIO.

AGRICULTURAL IMPLEMENT.

1,415,111.

Specification of Letters Patent. Patented May 9, 1922.

Application filed January 3, 1921. Serial No. 434,510.

To all whom it may concern:

Be it known that I, CHARLES H. PELTON, a citizen of the United States, residing at Springfield, in the county of Clark and 5 State of Ohio, have invented certain new and useful Improvements in Agricultural Implements, of which the following is a specification, reference being had therein to the accompanying drawing.

10 This invention relates to agricultural implements, and more particularly to grain drills which are to be operated or drawn over the fields by a tractor or power machine.

15 The present invention comprises an improvement upon that part of my other invention set forth in my application, Ser. No. 374,527, filed April 17th, 1920, which relates to the connection between the rock-shaft and the draft-operated eccentric mechanism.

20 As set forth in my earlier application the pitman connecting the eccentric ring with the arm on the rockshaft was of a fixed length, any adjustment in the relation of the eccentric ring and the arm on the rock-shaft depending upon a series of holes in the pitman, through either of which could be passed the pitman that connected the pitman with the arm. And in the former case the pitman was also rigidly connected with the eccentric ring.

25 In the present invention the length of the pitman is adjustable so that the gangs may be pressed more or less near the ground, and the hoes or disks more or less deep in the soil, by the given or fixed movement or throw of the eccentric ring.

30 And in the present case also the pitman is 40 flexibly connected with the eccentric ring so that any variance in the alignment between the ring and the arm on the rock-shaft which connects with the pitman will not tend to bind the ring on its operating devices.

35 These two improvements are of marked advantage in the practical use of a grain drill embodying my invention, as will be hereinafter more fully explained.

45 In the accompanying drawings:

50 Fig. 1 is a partial side and partial sectional view of a grain drill embodying my

present improvements and so much of the invention embraced in my former application, mentioned above, as is necessary to an 55 understanding of the present features:

Fig. 2 is an enlarged detail view of the pitman and eccentric ring and the manner of making the adjustable connection between them; and

Fig. 3 is a plan view of a drill showing generally the arrangement embodied in my former application, with my present invention substituted for the former pitman and eccentric ring.

60 As stated above, the present invention constitutes improvements on the part of the invention set forth in my previous application, Ser. No. 374,527. I will therefore make but a general description of so much of the 65 previous invention as is illustrated in the present case, confining the particularities of the specification to the present improvements.

Those parts of a general grain drill, which 70 are here shown, are ground wheels 1 (only one wheel is shown as both are alike) mounted on an axle or shaft 2 to which the wheels are so connected that the axle revolves with them. Suitably mounted upon the axle is 75 a frame comprised of longitudinal members 3 and cross members 4 and 5. To the forward members 4 are secured depending arms 6 braced by braces 7. In the arms is mounted a long cross rod 8 on which are hung 80 the beams or gangs 9 which carry the furrow opening disks 10 and seed delivery tubes 11. To each of these tubes is connected a lifting and depressing rod 12, which preferably has a series of openings 13 to receive 85 a pin 14 which supports a washer 15 on which rests a spiral spring 16, the other end of the spring pressing against a sleeve 17 slidably mounted on the rod 12 so as to move when pressure is applied to it and 90 thence to the spring in exerting a downward force to press the furrow-openers suitably into the ground. To this end the sleeve 17 is pivoted to an arm 18 connected with a squared rockshaft 19 mounted in bearings 95 100 on standards 20 which are sustained by the rear portion of the general frame.

Referring now to the draft-actuated lifting mechanism which is operated to lift the

beams or gangs from the ground, I would state that it is the same as that set forth in my other application and need be referred to here only to the extent necessary to show 5 the use and application of the present improvements. To this end it will be understood that the eccentric ring 21 receives eccentric motion so as to impart a substantial reciprocating motion to the pitman composed of the rod 22 and bar 23. This bar is pivoted to the ring by means of a bolt 24 passing through lugs 25 on the ring and through an opening in the adjacent end of the bar 23. The other end of the bar is in 10 the nature of a sleeve, screw-threaded interiorly to receive the threaded portion 26 of the rod 22. By these means the length of the pitman can be varied by screwing the rod in or out of the bar. To prevent the 15 rod from ever being wholly unscrewed from the bar, as when the machine might be out of use, a pin 26^a or other form of enlargement or interruption of the thread on the rod is provided so that when this point is 20 reached it will clog in the thread of the bar 23 and thus prevent the rod from being unscrewed wholly out.

The other end of the rod is provided with a shoulder 27 and passes through a coupling 30 28 and terminates in a crank 29. The coupling 28 is pivoted at 30 to an arm or projection 31 which is secured to the rock-shaft 19.

From all this it will be understood that 35 when the eccentric ring 21 is operated, as when the locking and unlocking mechanism, generally shown herein at 32, is operated to unlock the draft lifting-mechanism, the pitman will be given a rearward and upward movement. This is transmitted to the rock-shaft 19 through the coupling 28 and projection or arm 31. In turn, the arm 18 and the gang-lifting rod 12 are operated to lift 40 the gang or beam. This description applies 45 to all of a series of arms 18, rods 12 and gangs 9, say one-half of the whole number in a drill, like mechanism to that herein described being used to so operate the other half of the gangs through like rods 12, arms 50 18 and rockshaft 19.

It will now be seen that there must be either perfect alinement between the position of the eccentric ring and the arm 31 on the rockshaft or there must be some means 55 to compensate for any irregularity or lack of alinement between these parts. This is necessary in order to overcome a binding or twisting effect on the ring. To this end I pivotally connect the ring and the pitman in 60 the manner above described. In this way the pitman works freely and so does the ring, yet the ring may not be in perfect alinement with the arm 31 on the rockshaft. Or the alinement may be quite perfect when 65 the machine is first made, but may be lost

due to wear and strains. Nevertheless by this pivotal relation between the eccentric ring and the pitman my machine works perfectly under these several conditions.

And again, it will be seen that the distance between the eccentric ring and the arm 31 on the rockshaft may be varied, and made greater or less. This is done by revolving the rod 22 in the bar 23.

If the pitman is thus shortened and the 75 arm 18 on the rockshaft is brought near to the eccentric ring the given movements of the pitman and ring in permitting the furrow opener to descend to the ground will cause the furrow opener to go deeper into 80 the soil than if the distance between the eccentric ring and the arm 18 is lengthened. In other words, by means of this adjustable pitman the distance between the arm 18 on the rockshaft and the eccentric ring may be 85 varied to suit any and all practical conditions that arise in use.

While I have shown and described certain features as constituting my invention, it will be understood that parts have been shown 90 for purposes of illustration only, and that I do not desire to be limited to such details, as obvious modifications will occur to a person skilled in the art.

Having thus fully described my invention, 95 what I claim as new and desire to secure by Letters Patent, is:—

1. The combination with power transmitting mechanism, of a pitman secured thereto and adjustable in length, one member of the 100 pitman comprising a rod having a crank by which it is operated to adjust the length of the pitman, a rock shaft, and connections between the rock shaft and rod, said connections permitting the turning of said crank 105 without disconnecting the rod.

2. The combination, with power transmitting mechanism including an eccentric, of a pitman comprising a bar pivoted to the eccentric, a rod screwed into the bar and having a crank at the other end, a rockshaft, an arm thereon, and a coupling pivoted to said arm and receiving within it the pitman rod.

3. A pitman composed of a bar provided 115 at one end with an aperture to receive a pivot pin and having a screw-threaded sleeve, a rod screwed into said sleeve with a stop at one end to limit the adjustment of the rod in the sleeve, and a crank at the 120 other end.

4. The combination with a shaft and a frame supported thereby, a rock shaft carried by the frame, power transmitting mechanism mounted upon the first mentioned shaft and including an eccentric, a pitman provided at one end with an adjustable member pivotally connected to said eccentric, a crank provided at the other end of said pitman for adjusting said adjustable 125 130

member, and means connecting said pitman to said rock shaft.

5. In combination, an eccentric ring, a bar pivotally connected to said ring by a pivot pin extending perpendicularly to a radius of said ring, said bar being provided with a threaded aperture, a rod provided at one end with a crank and having its other end threaded in engagement with the threads of the aperture, and a member mounted upon said rod and actuated thereby.

6. The combination with a shaft and a frame supported thereby, of a rock-shaft carried by the frame and arranged parallel to the first mentioned shaft, power transmit-

ting mechanism mounted upon the first mentioned shaft, a pitman pivotally connected to said mechanism by a pivot pin having its axis arranged at an angle to the axis of said first mentioned shaft, said pitman being formed of a plurality of parts secured together by a threaded connection, a crank provided on one of said members for adjusting the threaded connections, and means connecting said pitman to said rock- 20 shaft. 25

In testimony whereof, I affix my signature.

CHARLES H. PELTON.
